(57) **CLAIM**

The ornamental design for a substrate-handling robot end effector, as shown and described.

DESCRIPTION

FIG. 1 is a top perspective view of a substrate-handling robot end effector in accordance with a first embodiment of the present design.

FIG. 2 is a bottom perspective view of the first embodiment of the present design.

FIG. 3 is a top view of the first embodiment of the present design.

FIG. 4 is a bottom view of the first embodiment of the present design.

FIG. 5 is a first side view of the first embodiment of the present design.

FIG. 6 is a second side view of the first embodiment of the present design.

FIG. 7 is a front view of the first embodiment of the present design.

FIG. 8 is a rear view of the first embodiment of the present design.

FIG. 9 is a top perspective view of a substrate-handling robot end effector in accordance with a second embodiment of the present design.

FIG. 10 is a bottom perspective view of the second embodiment of the present design.

FIG. 11 is a top view of the second embodiment of the present design.

FIG. 12 is a bottom view of the second embodiment of the present design.

FIG. 13 is a first side view of the second embodiment of the present design.

FIG. 14 is a second side view of the second embodiment of the present design.

FIG. 15 is a front view of the second embodiment of the present design; and,

FIG. 16 is a rear view of the second embodiment of the present design.

(Continued)

The broken lines shown in the figures are directed to unclaimed portions of the end effector and/or unclaimed components attached to the end effector that are for illustrative purposes only and form no part of the claimed design.
